UNITED STATES PATENT OFFICE.

THOMAS W. CORKELL, OF CHICAGO, ILLINOIS.

COLLAPSIBLE BARREL.

1,214,650.

Specification of Letters Patent. Patented Feb. 6, 1917.

Application filed December 24, 1915. Serial No. 68,513.

To all whom it may concern:

Be it known that I, THOMAS W. CORKELL, a citizen of the United States, and a resident of the city of Chicago, in the county 5 of Cook and State of Illinois, have invented certain new and useful Improvements in Collapsible Barrels; and I do hereby declare that the following is a full, clear, and exact description of the same, reference being had 10 to the accompanying drawings, and to the numerals of reference marked thereon, which form a part of this specification.

This invention relates to an improved type of collapsible barrel constructed of 15 wood, metal, composition or other material, but, as shown and described, preferably constructed of metal, to afford an exceedingly substantial structure.

It is an object, therefore, of this invention 20 to construct a collapsible metallic barrel wherein the metallic stave elements are constructed to afford hinge members to receive attaching pintle bolts therethrough, and with circular metallic arched heads for the 25 top and bottom ends of the barrel to fit tightly within and over the edges of the hingedly connected stave elements and to be bolted thereto to afford substantially a unitary structure.

It is also an object of this invention to 30 construct a collapsible metallic barrel wherein the staves are constructed of curved strips of metal with the margins thereof formed to afford hinge members to receive 35 pintles therethrough whereby the hingedly connected staves may be laid folded around the circular top and bottom metallic heads provided for the barrel, and with registering apertures provided between the ends 40 of said staves and the flanges on said heads to receive attaching connecting bolts therethrough.

It is also an object of this invention to 45 construct a knock-down or collapsible barrel wherein the staves are hingedly connected one to another and are adapted to interfit with circular heads which afford a brace and connecting means for the ends of the staves to hold the same disposed in proper cylindrical form, and with certain of said staves 50 adapted to be swung open from the built-up barrel to give access to the barrel through the side thereof.

It is furthermore an important object of 55 this invention to construct a collapsible barrel embracing flanged heads adapted to fit

over the staves which are hingedly connected to one another, with the heads so constructed as to protect and brace the upper ends of the staves and hold the same spaced in 60 proper relation with one another and suitably secured thereto to permit ready detachment therefrom.

It is finally an object of this invention to construct an improved type of knock-down 65 or collapsible barrel simple in construction and easy to arrange in assembled form.

The invention (in a preferred form) is illustrated in the drawings, and more fully pointed out and defined in the appended 70 claims.

In the drawings, Figure 1 is a side elevation of a barrel constructed according to the principles of my invention. Fig. 2 is a top plan view thereof. Fig. 3 is a fragmentary 75 interior view of the staves of the barrel. Fig. 4 is a horizontal section taken through the barrel, showing certain of the hingedly connected staves swung into open position to give access to the interior of the barrel. 80 Fig. 5 is a fragmentary sectional view illustrating the interior of the assembled barrel. Fig. 6 is a fragmentary horizontal sectional view similar to Fig. 4, but on a larger scale. Fig. 7 is a fragmentary plan view of the 85 under surface of a barrel head at a certain portion of the edge thereof. Fig. 8 is a fragmentary exterior view of the upper end of the barrel at that portion of the edge of the head shown in Fig. 7. Fig. 9 is a fragmentary detail section taken on line 9-9 of Fig. 5. Fig. 10 is a detail section taken on line 10-10 of Fig. 8, showing the removable locking rod for the opening stave sections of the barrel. Fig. 11 is a similar view at the 95 lower end of the barrel, illustrating the locking nut on said rod. Fig. 12 is a detail section taken on line 12-12 of Fig. 8. Fig. 13 is a detail section taken on line 13-13 of Fig. 1. 100

As shown in the drawings, the reference numeral 1, indicates one of a number of similarly constructed metallic barrel staves, each of which, on one side, has hinge members 2, formed integral therewith and on the other side thereof, similar hinge members 3, staggered with respect thereto, so that a number of said staves may be arranged with the hinged members thereof registering with one another to receive a hinge pintle bolt or rod 110 4, inserted therethrough. As clearly shown in Fig. 3, in the upper and lower ends, al-

though the lower ends of the staves are not shown, are recesses, as indicated by the reference numeral 5, at the corners thereof, so that two adjacent staves afford a recess for the rounded head 6, of the pintle rod 4, shown in Fig. 13. Certain of the staves of the barrel denoted by the reference numerals 7, 8, 9, and 10, are shorter than the remaining staves, and are adapted to be swung open into the position shown in Fig. 4, to give access to the interior of the barrel through the sides thereof. These stave elements are connected in a similar manner by pintle rods 4. Circular metallic heads are provided, which are exactly similar in construction, consisting of a main arched portion 11, with an upstanding flange 12, formed thereon, and with the margin 13, of said flange, as clearly shown in Figs. 9 and 13, bent over to afford a recess into which the upper ends of the stave elements 1, engage. That portion of the head, however, which is disposed at the ends of the shorter staves 7, 8, 9 and 10, has the small marginal flange struck or flattened inwardly, as denoted by the reference numeral 14, and best shown in Fig. 12, so as to abut against the ends of said aforesaid stave elements and yet not confining the same, so that the same may swing outwardly, as shown in Fig. 4.

At the junction of one end of the inwardly struck flange 14, with the outwardly projecting marginal flange 13, the metal is cut away to afford a recess to permit withdrawal of a locking hinge bolt or rod 15, the lower end of which is provided with a nut 16, as shown in Fig. 11. The purpose of so utilizing a removable hinge bolt 15, at this point in place of a hinge rod 4, is to permit release of the stave element 10, from the complementary stave element 1, so that the respective stave elements 7, 8, 9, and 10, may be swung into open position. The flanges 12, on said respective barrel heads are provided with apertures at certain points to receive inserted therethrough and through registering apertures provided in certain of the stave elements, small connecting or attaching bolts 17, each provided with a removable nut 18, said bolts and nuts at the top and bottom ends of the barrel acting to maintain the stave elements positively associated with the barrel heads and yet permitting ready detachment of the heads therefrom to collapse the barrel by folding the hinge staves one upon another when desired. An internal reinforcing ring 19, may be provided for the staves, if so desired, as shown in Fig. 5.

The operation is as follows: In assembling the barrel, the stave elements 1, are laid flat in interfitting relation with one another, *i. e.*, with the tubular hinge members 2, on one side of each stave element registering with the tubular hinge elements 3 of the stave elements laid adjacent thereto, and

the pintle rods 4, are then inserted therethrough. However, for those stave elements 7, 8, 9, and 10, which are identical with the construction of the stave elements 1, except that the former are adapted to be swung into open position such as shown in Fig. 4, the heads 11 for the top and bottom of the barrel are so constructed as to permit the aforesaid stave elements to be opened outwardly. This operation is permitted due to the fact that the marginal flange 14, which lies flat against the upright flange 12, of the barrel heads, merely abuts the ends of said stave elements 7, 8, 9, and 10, as shown in Fig. 12, thus permitting the same to be readily swung outwardly therefrom. On the other hand, the remainder of the peripheral marginal flange of each of the barrel heads which is denoted by the reference numeral 13, projects over and beyond the ends of the stave elements 1, interfitting therewith in the manner shown in Fig. 9, thus preventing the stave elements 1, being swung into an open position, and the bolts 17, and nuts 18, engaging through the flange of the barrel heads and the upper ends of said stave elements 1, serve to retain the barrel heads rigidly associated with the staves thereof. One of the junctions between the marginal flanges 13 and 14, is cut away at the upper and lower ends of the barrel to permit removal of the pintle rod 15, inserted through the hinge members 2 and 3, of the adjacent stave elements 1 and 10, at this point, so that the remaining stave elements 7, 8, 9, together with 10, may be swung into open position by removal of the pintle rod.

I am aware that various details of construction may be varied without departing from the principles of my invention. I therefore do not purpose limiting myself otherwise than necessitated by the prior art.

I claim as my invention:

1. A collapsible metal barrel, comprising a plurality of stave elements recessed at their corners, hinge members formed on each edge thereof with the hinge elements of one edge staggered with respect to those of another element, headed hinge pintle rods adapted to be inserted through the registering hinge elements of a number of staves laid adjacent one another, said recesses receiving the pintle heads, flanged heads adapted to be inserted into the cylindrical body formed by said stave elements, and marginal flanges on said heads adapted to engage over and around the ends of said stave elements to maintain the same in proper relation.

2. A collapsible metal barrel, comprising a plurality of curved staves, hinge members formed on each edge thereof in staggered relation adapting a number of said staves to be laid adjacent to one another

with the respective hinge elements thereof registering, pintle rods adapted to be inserted through the registering hinge members pivotally to connect said staves one to another, heads adapted to be inserted into the cylindrical body formed by said connected staves, and means for attaching said heads to said staves, certain of said staves being free to permit the same to be swung open to give access to the interior of the barrel through the side thereof.

3. A collapsible metallic barrel, comprising curved metallic staves some of which are shorter than the others, hinge members formed integrally on each side of each of said staves, pintle rods inserted through the registering hinge members to maintain said

staves pivotally connected to one another, and barrel heads around which said staves are adapted to be disposed and connected and provided with marginal flanges adapted to fit over the ends of the lower staves, said flanges being struck inwardly or flattened for a portion of their length so as to abut against the ends of the shorter staves to permit the same to swing outwardly to give access to the interior of the barrel.

In testimony whereof I have hereunto subscribed my name in the presence of two subscribing witnesses:

THOMAS W. CORKELL.

Witnesses:

CHARLES W. HILLS, Jr.,
EARL M. HARDINE.
